UNITED STATES PATENT OFFICE.

WILLIAM P. MOSELEY, OF STAMFORD, CONNECTICUT, ASSIGNOR TO THE YALE & TOWNE MANUFACTURING COMPANY, OF STAMFORD, CONNECTICUT.

KEY.

1,032,930.

Specification of Letters Patent.

Patented July 16, 1912.

Application filed February 24, 1912. Serial No. 679,727.

To all whom it may concern:

Be it known that I, WILLIAM P. MOSELEY, a citizen of the United States, residing at Stamford, in the county of Fairfield and State of Connecticut, have invented certain new and useful Improvements in Keys; and I do hereby declare the following to be a full, clear, and exact description of the invention, such as will enable others skilled in the art to which it appertains to make and use the same.

My invention relates to keys, the object being to provide keys with designating or identification numbers or marks, so concealed that said members or marks can only be seen and ascertained upon the removal of a part of the key, so that some identification or designating numbers or marks can be attached to the key in a concealed manner, and so that the numbers or marks thus concealed can not be fully identified from numbers or marks, with reference to its owner, its location or use, until part of the key is removed to expose the said numbers or marks, and so that such numbers or marks concealed within the recess can be changed without changing or disfiguring the exposed surface of the key.

With these objects in view my invention consists in a key having a recess in one face thereof, designating or identification numbers or marks stamped or otherwise formed or placed within said recess, and a plate detachably secured within said recess, and concealing the numbers or marks stamped or otherwise formed or placed within said recess.

In the accompanying drawings, Figure 1 is a view showing the completed key. Fig. 2 is the key with the plate removed showing a number or mark at the bottom of the recess. Fig. 3 is a view in section showing a means for securing the plate in place, and Fig. 4 is a view of the plate removed.

Fig. 1 represents a key of any approved form. In the drawings I have shown a Yale & Towne pin tumbler lock key, but the improvement is equally applicable to any key having a part sufficiently large to receive the cover or plate.

The key 1 is provided with a recess 2, in which numbers or marks are stamped or otherwise formed or placed. These numbers or marks may designate the key number, the room, safe or box number or any other de-

tails from which duplicate keys may be ordered, from the maker of the lock, or, of which other uses can be made. The recess 2 is normally closed by the plate 3, which latter may also be provided on its outer or inner face with designating numbers or marks. This plate is of a size and shape to approximately fill the recess and rest flush with the surface of the key, so that when in position, it presents the appearance of a fixed and permanent part of the key. This plate 3 is provided at one side with a small lip 4 adapted to enter a recess in the wall of the recess, and is engaged at its opposite side by the flange 5 of the eyelet 6 which latter passes through a hole in the key, and is preferably secured by upsetting or riveting its outer end, but may be secured in any other manner and is preferably made of thin pliable metal, so that it may be removed by suitable tools, thus permitting the plate 3 to be removed when it becomes necessary to see or to change the numbers or marks, which, as explained, are concealed by the said plate. These keys are particularly adapted for safe deposit boxes, and other places where there are to be a large number of locks in use, and where both convenience and safety to both the renter and rentee is desirable. In many cases it is desirable and necessary that the key number shall be unknown or concealed, while the box number or the other number or mark shall be known and exposed. My invention will enable the lock makers or others to place the key number where it cannot be seen, without taking the key apart, and to place any other designating number or mark outside and exposed, or, by my invention, to place such other number inside and concealed by the plate or cover, thus concealing all designating numbers or marks.

Where changeable combination key locks are used my invention provides a means for attaching numbers or marks and concealing them from view, adding increased safety in the use of such locks and keys where the numbers or marks might otherwise be placed on the exposed surface.

Where locks not of a changeable combination key type are used, it has been customary in some safe deposit companies to conceal the key numbers and the key bitting by inclosing the keys in sealed en-

velops, or the locks and keys in sealed packages, to conceal both the keys and their numbers or marks, also the tumblers of the locks until selected by a tenant. Where such methods are to be followed, my invention, if used, would still further increase the security of the renter and rentee, by concealing the key numbers or marks and would also provide a means of adding other numbers or marks in a concealed manner within the said recess, and also provide a way to change any of such marks or numbers concealed within said recess without disfiguring the exposed surface of the key.

It is customary in many companies and banks to provide a list of the key numbers, so that in the event of the loss of one or more keys issued to the rentee for any particular lock, the company may furnish the lock maker with the key number and proper authority, and thereby procure duplicates for the rentee, thus saving unnecessary expense by forcing or otherwise opening the door. By the use of my invention it will now be possible for the company or bank to avoid keeping this record, and at the same time, avoid confusion or excessive cost where keys are lost, for example: the keys can be ordered originally to have the key numbers or marks concealed by a plate or cover (the plate may or may not be marked on either surface with the box number or other designating number for convenience). When one of these locks is rented the keys can be given to the rentee with directions or

device for removing the plate or cover, and the rentee can then make record of, or remove the number or mark, and replace the plate or cover or a new one with or without additional concealed or exposed numbers. 40 This provides for the ready re-production of keys or any particular lock, without the necessity of exposing the key or other number or mark to the attendants, clerks or officials of the renting company. 45

Having fully described my invention what I claim as new and desire to secure by Letters-Patent, is:—

1. A key provided with a recess, a designating number stamped or formed within 50 said recess, and a removable cover plate fitting said recess and concealing said designating number, so that until said plate is removed the number in said recess cannot be seen.

2. A key provided with a recess, a removable plate fitting said recess and provided at one edge with a tongue adapted to enter a socket in the wall of the recess, and a detachable rivet secured to the key with its 60 flange overlapping the edge of the plate at the side opposite the tongue.

In testimony whereof I have signed this specification in the presence of two subscribing witnesses.

WILLIAM P. MOSELEY.
